FIXTURE FOR SUPPORTING AND GAUGING
BRUSH RIGGINGS OF MOTORS AND GEN-
ERATORS

Herbert E. Krueger, Vallejo, Calif.

Application October 26, 1945, Serial No. 624,924

8 Claims. (Cl. 33—181)

(Granted under the act of March 3, 1883, as
amended April 30, 1928; 370 O. G. 757)

1

This invention relates to supporting fixtures and more particularly to adjustable fixtures for checking and setting the brush riggings of motors and generators.

An object of the invention is to provide an improved supporting fixture of such construction as will permit the accurate checking and setting of substantially all types of brush riggings, brackets, yokes and brush boxes of motors and generators.

Other objects of the invention are to provide an improved supporting fixture, of the character described, wherein inaccuracies in the direct or angular relation of the brush rigging, brackets, yokes and brush boxes to the commutator may be readily ascertained; to provide an improved supporting fixture which is particularly adaptable for use in connection with large brush riggings of the main propulsion motors and generators of submarines; to provide an improved supporting fixture of the character described which is readily adjustable so as to accommodate brush riggings and yokes of various size; and to provide improved elements and arrangements thereof in a supporting fixture of the character described and for the purposes set forth.

In accomplishing these and other objects of the present invention, I have provided improved details of structure, the preferred form of which is illustrated in the accompanying drawings, wherein:

Fig. 1 is a top plan view of a portion of a supporting fixture embodying the features of the present invention.

Fig. 2 is an enlarged, transverse, vertical, sectional view, taken on the line 2—2 of Fig. 1.

Fig. 3 is an enlarged, transverse, vertical, sectional view, taken on the line 3—3 of Fig. 1.

Fig. 4 is a transverse, vertical, sectional view, taken on the line 4—4 of Fig. 1.

Referring more in detail to the drawings:

In Fig. 1, the numeral 1 designates a tripodod base or frame having an annular, central plate or ring 2 and a trio of radial members or arms 3 projecting outwardly from the ring preferably in equally-spaced relation. Each arm 3 is preferably of channel shape and has a central, longitudinal opening or slot 4 extending substantially throughout the length thereof. A pair of flat bars 5 underlie the longitudinal margins of each arm on either side of its slot 4 for reinforcing the arm. A vertical post or leg 6, having a caster ball 7 at its lower end, is disposed beneath and adjustably secured to each arm by a pair of short bolts or screws 8 which project through

the slot of the arm. The bolts 8 are carried by a flanged collar or cap 9 which is mounted upon the upper end of the leg 6 and confined between the longitudinal margins of the channel-shaped arm.

For supporting the yoke (not shown) of a brush rigging, an upstanding supporting member or block 10 is carried by each arm 3 and is adjustable longitudinally thereof. It is preferable to fasten the blocks 10 in adjusted positions by means of the bolts 8 which are screw-threaded into the bottoms of said blocks as shown in Fig. 4, whereby the blocks are movable along the arms with the legs 6. Each block includes 15 a flat, base plate 11 upon which a vertical plate 12 is welded or otherwise secured. The latter is reinforced by lateral buttress plates 13 which are welded or otherwise secured to the plates 11 and 12. A shoulder 14 is formed at the upper end of each block by recessing or removing the inner, upper portion thereof, and this shoulder is adapted to support the yoke of the brush rigging. In order to provide a minimum contact point for the yoke, a suitable upright screw 15 is recessed in the vertical face of the shoulder 14.

The base ring 2 has a depending collar 16 and is adapted to rotatably receive an upright, cylindrical supporting arbor or spindle 17 (Fig. 4). An annular plate or flange 18 is formed intermediate the ends of the spindle 17 so as to overlie and rest upon the base ring, while the shank or lower portion 19 of said spindle is journaled within the ring collar 16 and is held against upward displacement by a suitable nut 20 screw threaded upon the lower portion thereof. The upper extremity of the spindle is of enlarged diameter and is slotted transversely for slidably receiving a radial gage arm 21. A pair of nuts 22 are screw threaded upon the enlarged upper extremity of the spindle, above and below the gage arm 21, so as to clamp said arm in radially adjusted positions. One end of the gage arm carries a perpendicular gage bar or blade 23 which is fastened thereto by a suitable collar 24.

Above the gage arm, an angular centering head 25 is rotatably mounted on the upper end of the spindle 17 for slidably receiving a radial scale bar 26 having graduations thereon. The latter is held in adjusted radial positions by means of 50 a clamp ring 27 and a nut 28 which is screw threaded upon the upper end of the centering head 25. A suitable pin or bolt 29 depends vertically from one end of the scale bar 26 for rotatably supporting a small cylindrical sleeve 30 55 which is adapted to coact with the contact screws

3

15 of the blocks 10 in adjusting the positions of the latter.

As is clearly shown in Figs. 2, 3, and 4, the spindle flange 18 has its external periphery stepped or offset to provide a pair of concentric, horizontal shoulders 31 and 32. An outer annulus or ring 33, having an inner peripheral

to substitutional sites in the stock and to effete.

and maintain a brush rigging in a fixed position, the frame including an annular plate secured to and joining the inner ends of said arms, an upright support having a circular flange rotatably mounted in the plate, a radial gage arm slidably carried by the upper portion of the support at a right angle thereto, clamp means for fastening the gage arm in radially adjusted positions, a protractor ring encircling the periphery of said plate and rotatable relative thereto, means for clamping the protractor ring in a fixed position relative to the plate, a coaxial ring rotatably mounted on the support flange and having a radial pointer cooperating with said protractor ring, means for clamping the coaxial ring in a fixed position relative to said support flange whereby the pointer travels along the protractor ring upon rotation of said support, an annulus rotatably mounted upon the support flange and concentrically surrounding the support flange and coaxial ring, means for clamping the annulus to said coaxial ring whereby said annulus is rotatable therewith, the annulus having equally-spaced openings in its outer periphery, a retractable spring-pressed latch secured to the upper surface of the plate and adapted to engage within the openings of said annulus for maintaining the latter in a fixed position relative to said plate, and a radial scale slidably carried by the upper portion of the support for adjusting the positions of the supporting legs and blocks.

2. A supporting fixture including, an annular base, the base having horizontal radial arms, a vertical leg underlying and supporting each arm, a block adjustably fastened to and movable longitudinally of each arm, the blocks coacting with one another to maintain a brush rigging in a fixed position, an arbor rotatably vertically mounted in the base and having a circular flange, a radial gage arm slidably carried by the upper portion of the arbor, a protractor ring rotatably mounted upon and encircling the periphery of the base, a lock ring rotatably mounted on the flange of said arbor, means for fastening said lock ring thereto in adjusted fixed positions, the lock ring having a pointer cooperating with the protractor ring, an annulus rotatably mounted upon the arbor and concentrically surrounding the arbor and said lock ring, the latter having means for adjustably fastening said arbor and annulus whereby the lock ring, arbor and annulus may be rotated together or relative to each other, said annulus having recesses formed therein, and latch means carried by the base and adapted to engage within the annulus recesses for locking said annulus in adjusted positions relative to said base, the engagement of the latch means within one of said recesses preventing rotation of the arbor when the lock ring is fastened to the annulus and said arbor.

3. A supporting fixture including, a base having an annular portion and outwardly-directed radial portions, supporting means adjustably fastened to the radial portions and movable relative thereto radially for maintaining brush riggings of various diameters in fixed positions, a support rotatably mounted axially in and extending axially from the annular portion of the base, a gage arm slidably carried by a portion of the support axially remote from said annular portion of said base, an annular protractor element rotatably mounted upon said annular base portion, a first annular member rotatably mounted on said support and having pointer means cooperating with the protractor element, a second annular member rotat-

ably mounted on the support, retractable means carried by the annular base portion for locking the second member against rotation in adjusted positions, and means for adjustably fastening the first member to said support and second member whereby the supports and members may be rotated together or relative to each other.

4. A supporting fixture including a base, support means mounted on said base and adjustable relative thereto radially of an axis extending from said base, gage supporting means rotatably mounted on said base for motion about said axis and having a portion extending axially along said axis from said base, a radial gage carried by a portion of said gage support means remote from said base, a protractor element carried by the base, a first member rotatably mounted on said gage supporting means and having pointer means cooperating with the protractor element, a second member rotatably mounted on the gage supporting means, means for locking the second member to the first member and said gage supporting means whereby the same may be rotated relative to each other or together, and means carried by said base for locking said second member against rotation.

5. A supporting fixture including a base, support means mounted on said base and adjustable relative thereto radially of an axis extending from said base, gage supporting means mounted on said base for rotation relative thereto about said axis, a gage carried by said gage supporting means and extending radially of said axis, a pair of rotatable members concentric with said axis and mounted on said gage supporting means, one of the members having index means, a protractor element carried by the base for cooperating with the index means, means for locking said members to each other and to the gage supporting means whereby the same may be rotated relative to each other or together, and means for locking one of the members against rotation relative to said base.

6. A supporting fixture for brush riggings including a base, supports mounted on said base and adjustable radially thereof relative to an axis extending from said base, a rotatable element mounted on said base, gage means carried by said element extending radially of said axis, a pair of rotatable members mounted on said element means for locking the members to each other and the element whereby said members and element may be rotated relative to each other or together, and means for locking one of the members against rotation relative to said base.

55. 7. A supporting fixture including a base, support means mounted on said base and adjustable relative thereto radially of an axis extending from said base, rotatable supporting means mounted on said base, a gage carried by said rotatable supporting means and extending radially of said axis, a pair of rotatable members concentric with said axis and mounted on said rotatable supporting means, one of the members having index means, a protractor element carried by the base for cooperating with the index means, means for locking said members to each other and to the rotatable supporting means whereby the same may be rotated relative to each other or together, and means carried by said base for coacting with one of the members to limit rotation of said member and lock the same in adjusted positions.

8. A supporting fixture for brush riggings including a base, supports mounted on said base and adjustable relative thereto radially about an axis extending from said base, a rotatable element

mounted on said base, gage means carried by said element and extending radially of said axis, a pair of rotatable members mounted on said element, means for locking the members to each other and the element whereby said members and element may be rotated relative to each other or together, and means carried by said base for coacting with one of the members to limit rotation of said member and lock the same in adjusted positions.
